United States Patent Office

Des. 228,612
Patented Oct. 16, 1973

228,612

DRILL GUIDE

Laird F. Covey, Easton, Conn., assignor to The Stanley Works, New Britain, Conn.

Filed Dec. 2, 1971, Ser. No. 204,409

Term of patent 14 years

Int. Cl. D8—05

U.S. Cl. D8—14

FIG. 1

FIG. 2

FIG. 3

FIG. 6

FIG. 7

FIG. 1 is a perspective view of a drill guide showing my new design;

FIG. 2 is a top plan view thereof;

FIG. 3 is a bottom view thereof;

FIG. 4 is a side elevational view thereof;

FIG. 5 is an elevational view of the side opposite that illustrated in FIG. 4;

FIG. 6 is a front-end elevational view thereof; and

FIG. 7 is a rear-end elevational view thereof.

I claim:

The ornamental design for a drill guide, as shown.
